INVENTOR

Emery Parker

United States Patent Office.

EMERY PARKER, OF NEW BRITAIN, CONNECTICUT, ASSIGNOR TO RUSSELL AND ERWIN MANUFACTURING COMPANY, OF SAME PLACE.

Design No. 3,387, dated February 23, 1869.

DESIGN FOR THE FACE-PLATE OF A LOCK.

The Schedule referred to in these Letters Patent and making part of the same.

To all whom it may concern:

Be it known that I, EMERY PARKER, of New Britain, in the county of Hartford, and State of Connecticut, have originated and designed a new Design for the Face-Plate of a Lock, or Latch; and I do hereby declare that the following specification, taken in connection with the drawings making a part of the same, is a full, clear, and exact description thereof.

In the drawings—

A represents the face-plate of a lock;

B, the bolt; and

C, the latch.

In order to give an ornamental effect to the plate, which, when the lock is placed in its mortise in the door-stile, becomes, when the door is open, exposed to view, I surround the edge of the plate with a raised

moulding, *a*, whereby the effect of a sunken panel is obtained, and a novel and distinctive appearance given to the plate. I also prefer to surround the openings in the plate for the bolt and the latch with a similar moulding, as shown in the drawing.

What I claim as my invention, and desire to secure by Letters Patent, is—

The design for the face-plate of a lock or latch, which consists in surrounding the edge of the plate, or its edge and that of the bolt and latch-mortises, with a moulding, as herein set forth, and shown in the drawings.

EMERY PARKER.
